United States Patent Office

Des. 186,638
Patented Nov. 10, 1959

186,638

TELEPHONE INDEX

Julius A. Kerpel, New York, N.Y.

Application October 1, 1958, Serial No. 52,830

Term of patent 14 years

(Cl. D74—1)

Figure 1 is a side perspective view of a telephone index, showing my new design as it appears in partially opened position;

Figure 2 is a side perspective view thereof as it appears in closed position;

Figure 3 is a front elevational view;

Figure 4 is a top plan view;

Figure 5 is a side elevational view thereof.

I claim:

The ornamental design for a telephone index, substantially as shown.
